LIGHT SEAL CURTAIN

Louis F. Julien, Detroit, Mich., assignor to Chamberlin Metal Weather Strip Co., Detroit, Mich., a corporation of Michigan

Application January 14, 1937, Serial No. 120,491

5 Claims. (Cl. 156—10)

This invention relates to a light excluding shade or curtain for windows or other openings in the walls of laboratories, moving picture, operating, X-ray and other rooms from which it is essential that every outside ray of light be excluded.

An object of the present invention is to so mount a curtain for this purpose as to preclude the entrance of any light through or around the edge portions of the curtain when in closed position, and to provide for free manipulation of the curtain to admit light when so desired. It is also an object to provide means for guiding and holding the edges of such a curtain to permit free movement of the curtain and at the same time prevent its edges from withdrawal from such guiding means when manipulated, thus dispensing with the necessity for cross bracing or stiffening strips for the curtain, and to so enclose and protect these edges of the curtain as to prevent every light ray from passing these edges or through minute openings therein formed by a needle in stitching adjacent these edges to form a hem therealong, said hem being adapted to cooperate with said guiding and holding means in guiding and holding the edges of the curtain and in permitting limited transverse movement and free longitudinal movement of the curtain.

It is also an object to provide supplemental side edge guiding means for the curtain which means is adapted to be received in such edge hems to assist in holding the edges of the curtain within guide channels and permit free longitudinal movement of the curtain when manipulated to admit light, said supplemental guiding means having a limited lateral movement to prevent the curtain from binding thereon, and preferably being in the form of rods engaged within the side edge hems of the curtain and upon which the curtain is adapted to slide.

It is also an object to further insure the complete exclusion of light and effectual holding and guiding of the curtain, by providing a rigid frame having side channels to receive the edge portions of the curtain and said supplemental guide rods, said frame being adapted to fit tightly within the wall opening or window casing and to be rigidly secured therein, said channels being so formed as to be closed to the passage of light therethrough by said edge portions and rods, said portions being held against withdrawal through the open sides of said channels, by said guide rods engaged in said curtain hems within said channels.

It is also an object of the invention to prevent any light rays from passing around the lower end

of the curtain by providing a draw bar for said end and providing a fixed sill member to receive said draw bar, said sill member and bar cooperating when interengaged, to block the light; and it is also an object to provide means for winding up the curtain, such as a spring roller to which the upper end of the curtain is attached, this roller being enclosed within a light excluding casing to prevent light rays from passing the upper end of the curtain, said casing being arranged to facilitate the mounting of the roller therein.

A further object is to provide certain other new and useful features in the construction, arrangement and combination of the several parts adapted to promote the several objects of the invention, all as hereinafter more fully described and shown in the accompanying drawings, in which

Figure 1 is a front elevation, with parts broken away and in section, of a structure illustrative of an embodiment of the present invention;

Fig. 2 is a transverse section substantially upon the line 2—2 of Fig. 1 and through the window and casing to which the structure is applied as illustrated in Figs. 2 and 3;

Fig. 3 is a vertical section substantially upon the line 3—3 of Fig. 1;

Fig. 4 is a vertical section substantially upon the line 4—4 of Fig. 1;

Fig. 5 is a sectional detail substantially upon the line 5—5 of Fig. 1, and

Fig. 6 is a sectional detail substantially upon the line 6—6 of Fig. 1.

In Figs. 2 and 3 of the accompanying drawings, the curtain and structure embodying the present invention, is shown as applied to the usual window frame including upright sides or stiles 1 providing ways for sash frames 2, said window frame including a header 3 and sill 4; but it will be understood that the present structure may be applied as well to any opening in a room wall, from which room it is desired to exclude the light, said structure including a rectangular frame of a size to fit closely within the wall opening or window frame and be secured in place therein, making a tight joint therewith, all along the top, bottom and sides of the opening. This frame provides a mounting for the curtain which is indicated as a whole by the numeral 5 and is preferably formed of a flexible fabric coated upon both sides with a suitable material to make it absolutely impervious to light rays.

To house, hold and guide the side edges of this curtain, the main rectangular frame 6 which is formed of bar stock of rectangular form in cross section, and which frame is of the proper dimen-

sions to fit within the opening to be closed by said curtain, is provided along its vertical side members, with inwardly projecting channels, by securing sheet metal strips 7 to opposed faces of each side member of the frame 6, these strips forming between them, an outer channel 8 along the frame member and an inner channel 9 which is open between the free inner edges of said strips, said channels being connected by a connecting neck portion 10 formed by depressing each strip inwardly toward the other along a longitudinal line with a limited space between the walls of the neck just sufficient to permit the edge portions of the curtain to pass therethrough and slide freely therein, the edge portions of the curtain being each formed with a hem 11, each extending into each of the outer channels 8.

The side edges of the curtain are thus guided by these channels and said hems are housed therein so that no ray of light may pass through any minute hole in the curtain formed by the needle in stitching the hem, and to prevent the withdrawal of these edge portions laterally from either of said channels, a side guide rod 12 extends longitudinally within each hem and within each channel throughout the length thereof, each rod being loosely anchored at its lower end within the lower end of each of said channels 8 by forming each rod with a head 13 connected to its lower end by a reduced portion passing through a slot 14 in a bracket 15 secured to the frame 6. The curtain hems 11 thus slide freely upon these rods as the curtain is raised or lowered, binding of the hems upon the rods being prevented by the loose anchoring of each rod at its lower end only, so that it may move laterally a limited distance under a pull exerted thereon by lateral pressure on the curtain, and this movement is limited by the rods in said hems, being moved thereby, toward the neck portion 10 of each channel, said neck being too narrow to permit the rod and hem to pass therethrough. The curtain is thus guided along each side edge and each edge is so confined in its channel that it can not be withdrawn from either channel by lateral pressure on the curtain. Free sliding movement of the curtain upon said rods is further insured and the lower end of the curtain connected to said rods by providing a short sleeve 16 slidable upon each rod and inserted in the lower end of each hem and secured therein by a suitable clamping member 17 embracing said sleeve and end portion of said hem, said sleeves being each formed with a laterally extending arm 18 passing through the neck portion 10 between the channels 8 and 9 and into the latter where it is rigidly secured in any suitable manner to a draw bar 19 secured to and extending across the lower end of the curtain.

This draw bar as shown in cross section in Fig. 3, is preferably formed up of sheet metal into channel form with the channel open at its upper side and into which open side the lower end of the curtain is inserted, said end being formed with a hem 20 in which a metal strip 21 is inserted and this hem with said metal strip therein is secured within said channel by a locking strip 22 above the strip 21 and rigidly secured in place, confining said hem within the channel so that no light ray can pass through any holes formed by the needle in sewing the hem, and the lower end of the curtain is rigidly held against pulling loose and is accurately guided.

In order to prevent any light rays from passing around or beneath said draw bar when the curtain is in fully lowered position, a sill channel

member indicated as a whole by the numeral 23 is formed of sheet metal by securing the sheet metal forming the side walls of the channel firmly to opposite sides of the bottom cross member of the main frame 6 and to the lower ends of the side ways or channels which are received within the ends of said sill channel which is open at its upper side to receive said draw bar when the curtain is lowered to the limit of its movement, and therefore, as this sill channel is secured tightly against the window sill, no light can pass, and to further preclude the possibility of any light passing around the lower edge of the draw bar when within the sill channel, an outwardly projecting flange 24 is formed on the upper edge of the outer wall of the draw bar channel to project over the upper edge of the outer wall of the sill channel 23, the outer edge portion of this flange 24 being downturned as at 25 at less than a right angle to closely engage the said wall of the sill channel within the angle of said flange, and to further insure against the passage of light, the upper edge of the inner wall of draw bar channel is turned inwardly to form a flange 26 to project over the upper edge of the inner wall of said sill channel.

As shown in the drawings, the curtain is shown as partly lowered with said draw bar held at a short distance above and out of the sill channel by a pull cord 27 passed around a pulley 28 anchored to the lower part of the inner wall of the sill channel, with the free end of said cord detachably held by a spring clip 29, said curtain being held under spring tension tending to raise it, by securing its upper end edge to a spring actuated roller 30 extending across the upper end of the main frame 6 and mounted at its ends in bearings on brackets 31 secured to said frame, said roller being of the usual curtain roller construction having the usual coiled spring 32 exerting a force tending to turn the roller in a direction to wind the curtain thereon.

To tightly enclose said roller 30 and curtain wound thereon so that no light can possibly pass, a sheet metal casing 33 extends across and is secured to the upper end of the main frame 6, said casing having top, back and end walls permanently secured to said frame and a front and lower side wall forming a detachable closure 34, the upper edge of which is engaged within a groove formed along the edge of the top wall to make a tight joint as at 35, and said closure is detachably held in place by screws 36 engaging openings in the outer ends of the brackets 31. The upper ends of the side guides each formed by the channels 8 and 9 extend into and are rigidly secured at their upper ends within the ends of said casing which is thus tightly closed except along the lower edge of said closure which provides a slot through which the curtain passes, and thus all light is prevented from passing the upper end of the curtain over said roller or around its ends.

A spring roller is shown for winding the curtain thereon but it will be understood that any other suitable means may be employed for raising and lowering the curtain and holding it under tension when lowered, and to guide the curtain to this roller, a roll of small diameter 37 is mounted within the casing and adjacent said entrance slot for the curtain. The curtain may also be quickly demounted for replacement or repair by removing the closure 34 and then demounting the roller 30 with the curtain wound thereon, slipping the hems 11 and sleeves 16 from the upper ends of the guide rods 12 which ends

are tapered as at 38 to assist in again entering them into the hems when the curtain is replaced.

By thus mounting the flexible light impervious curtain within a frame of a size to fit closely within an opening in the wall of a room or in a window frame, every ray of exterior light is excluded from the room when the curtain is lowered, and by guiding the edges of the curtain within channels and providing means having limited lateral movement within these channels upon which the curtain is free to slide, for preventing the withdrawal of the curtain edges laterally from said channels under pressure from the inside or outside upon the curtain, free movement of the curtain is insured and no cross bracing of the curtain is necessary.

Obviously changes in the construction, arrangement and combination of parts may be made without departing from the spirit of the invention and such changes are contemplated.

Having thus fully described my invention what I claim is;

1. A light excluding structure including a frame to fit closely within an opening and provided with inwardly open opposite side channels, the opposite side walls of each channel being bent inwardly to form a narrow space therebetween, a flexible light impervious curtain within said frame with the opposite edges of said curtain engaged within said side channels of said frame, said edge portions of said curtain being formed with hems, and a guide rod within each side channel of the frame extending into said hems and upon which said hems are slidable, each of said rods being mounted at an end thereof for substantial movement in a lateral direction.

2. A structure of the character described including a rigid rectangular frame, sheet metal strips secured to opposite sides of the side members of said frame and forming inwardly open channels, the side walls of each channel being formed inwardly to provide a neck portion outwardly from the open inner side of each channel, a flexible light excluding curtain having opposite side edge hems within said channels, a guide rod within each channel extending longitudinally thereof within the hem therein of a greater diameter than the width of said neck portion, each rod being anchored at its lower end by slotted engagement with a stationary member and having free limited lateral movement within each channel, and means to which one end of said curtain is connected for winding the curtain thereon and holding said curtain under tension.

3. In a structure for the purpose described including a rigid rectangular frame, sheet metal strips secured to opposite sides of the side members of the frame to form channels opening inwardly of the frame, each channel being contracted intermediate its outer and open sides to provide a longitudinal neck portion in each channel, a light impervious flexible curtain within said frame having edge hems extending through the neck portions of said side channels, a guide rod within each side channel and within each of said hems and upon which said hems are free to slide, said rods being each of a diameter equal to or greater than the distance between the walls of said neck portions of said channels, a short

sleeve slidable upon each rod and to which the lower end of each hem is secured, a draw bar of channel form to receive the lower end of said curtain and within which said end of said curtain is secured, each of said sleeves having an arm extending inwardly through each of said side channels and secured to the ends of said draw bar, a rigid channel extending across the lower end of said frame and open at its upper side to receive said draw bar when the curtain is lowered, said draw bar having laterally extending flanges to project over the upper edges of said end channel of the frame and close said channel.

4. A structure for the purpose described including a rigid rectangular frame having opposite vertical side members provided with inwardly open channels extending throughout a major portion of the length of said frame, a light impervious curtain within said frame having side edge portions projecting into said channels and formed with longitudinal hems, a rod within each side channel projecting into each of said hems for guiding and holding the curtain at each edge, said guide rods at their lower ends being in slotted engagement with said frame within said channels for limited lateral movement to prevent binding within said hems, a draw bar secured to and extending across the lower end of said curtain and provided at each end within each side channel with a guide sleeve through which sleeves said rods extend, said sleeves being secured to the lower ends of said hems, a spring roller at the upper end of said frame and upon which said curtain is adapted to be wound, and a transverse member extending across the lower end of said frame to receive said draw bar when said curtain is lowered and enclose said draw bar and lower end of said curtain.

5. A structure for the purpose described including a rigid rectangular frame having opposite vertical side members provided with inwardly open channels extending throughout a major portion of the length of said frame, a light impervious curtain within said frame having side edge portions projecting into said channels and formed with longitudinal hems, a rod within each side channel projecting into each of said hems for guiding and holding the curtain at each edge, a draw bar secured to and extending across the lower end of said curtain and provided at each end within each side channel with a guide sleeve through which sleeves said rods extend, said sleeves being secured to the lower ends of said hems, a spring roller at the upper end of said frame and upon which said curtain is adapted to be wound, and a transverse member extending across the lower end of said frame to receive said draw bar when said curtain is lowered and enclose said draw bar and lower end of said curtain, said transverse member including an upwardly open channel and said draw bar being of channel form open upwardly to receive the lower edge of said curtain, said draw bar having laterally extending flanges for engaging over the upper edges of said transverse channel when said draw bar enters said latter channel upon the lowering of said curtain.

LOUIS F. JULIEN.
